UNITED STATES PATENT OFFICE.

JOSEPH DONAT BERGERON, OF IBERVILLE, QUEBEC, CANADA.

SNOWPLOW.

1,389,118.

Specification of Letters Patent. Patented Aug. 30, 1921.

Application filed September 9, 1920. Serial No. 409,268.

To all whom it may concern:

Be it known that I, JOSEPH DONAT BERGERON, a subject of the King of Great Britain, residing at Iberville, Province of Quebec, Canada, have invented certain new and useful Improvements in Snowplows; and I do hereby declare that the following is a full, clear, and exact description of the invention, such as will enable others skilled in the art to which it appertains to make and use the same.

The present invention relates to new and useful improvements in snow plows.

The primary object of the invention is the provision of a snow plow adapted for use in connection with railway tracks and the like, and which is connected to the forward part of a car or train for the purposes of removing the snow from the sides of the track. Another object of the invention is the provision of a snow plow including a pair of laterally extending wings hingedly connected to the opposite sides of a train or car adjacent the forward end thereof and extending upon opposite sides of the track for the purposes of clearing the same from snow and the like.

A further object of the invention is the provision of a snow plow such as above described, including a pair of hinged wings applicable principally to the cow-catcher or forward part of an engine, and which are so connected thereto that they may be swung forwardly out of the way, or for dumping purposes if desired.

A still further object of the invention is the provision of a snow plow such as above referred to, which will be comparatively simple and inexpensive to manufacture, reliable and efficient in use, and readily operated.

With the above and other objects in view, the present invention resides in the novel features of construction, formations, combinations and arrangements of parts to be hereinafter more fully described, claimed and illustrated in the accompanying drawing forming a part of the present application, and in which:

50 Figure 1 is a front elevation of the invention;

Fig. 2 is a top plan view thereof; and
Fig. 3 is a side elevation thereof.

Referring now to the accompanying draw-

ing by corresponding characters of reference throughout the several views, the numeral 4 designates in general the rails of a railway track section, while 5 denotes a cow-catcher or the like to be mounted upon the forward end of an engine or car, the latter not being shown, as it forms no part in the application.

The cow-catcher 5 consists preferably of a support 6 at the lower end of which extend the forwardly converging side members 7 connected to the support 6 by the upwardly inclined spaced bars 8.

The plow consists of a pair of wings 9 formed from any suitable material. These members are curved rearwardly, as shown at 10, and are disposed at an angle at 11, so that snow or the like engaging the same would be deflected toward the ends thereof and deposited in spaced relation to the rails 4.

The outer sides of the wings are shown substantially vertical, as at 12. The inner sides thereof are likewise disposed vertically, as at 13, a portion of their length and are then inclined forwardly, as at 14, producing inwardly directed extensions 15 which are disposed in parallel relation to the side members 7.

The upper and lower sides are extended forwardly, as at 16 and 17, forming a scoop for gathering up the snow which is, as above stated, deflected toward the outer ends of the said wings.

The upper and lower portions 16 and 17 are connected by spaced rods 18 which prevent the wings from becoming bent out of shape when engaged by banks of heavy snow. These rods 18 also serve to break up the snow into small particles in the event that the same has become partially melted and packed into a solid mass.

The opposite inner corners of the wings are provided with suitable eyes 20 and 21 which are secured, as at 22 and 23, to the upper ends of the outer bars 8 and intermediate portions of the side members 7, as clearly shown in the several figures of the drawing.

When it is desired to throw the wings to an inoperative position, they can be swung forwardly and upwardly on their hinged connections, as shown in Figs. 2 and 3 by the dotted lines. This serves to move the

wings out of the way when desired and also to scoop out or dump any snow which has become clogged therein.

From the foregoing description taken in connection with the accompanying drawing, it will be manifest that a snow plow is provided which will fulfil all of the necessary requirements of such a device, and it should be understood in this connection, that various minor changes in the specific details of construction can be resorted to within the scope of the appended claims, without departing from the spirit or sacrificing any of the advantages of the invention.

Having thus fully described the invention, what I claim as new and desire to protect by Letters Patent is:—

1. In a device such as described, the combination with a cow-catcher, a pair of wings hinged to the opposite sides thereof, said wings being concaved and extended at an angle rearwardly toward the outer ends thereof, and bars connecting the upper and lower portions of the wings.

2. In a plow such as described, the combination with a cow-catcher of a pair of wings hinged at their inner sides to the opposite sides of said cow-catcher, said wings being concaved and extended rearwardly at an angle, bars connected to the opposite for-

ward edges of the wings and arranged in parallel relation to each other, and means for hingedly connecting the wings to the cow-catcher.

3. In a snow plow such as described, the combination with a cow-catcher including the lower converging bars and upwardly extending inclined bars, wings disposed upon opposite sides of the cow-catcher, said wings having their side edges extended in parallel relation to the upwardly inclined bars and extensions provided at the inner lower corners of the wings disposed in parallel relation to the converging bars, the inner ends of said extensions being hingedly connected to the intermediate portions of the converging bars, and the upper inner corners of the wings being hingedly connected to the upper ends of the outer upwardly inclined bars, said wings having their upper and lower edges extended forwardly and being concaved throughout their lengths and extended rearwardly at an angle, and spaced parallel bars connecting the upper and lower portions of the wings, substantially as and for the purposes set forth.

In witness whereof I have hereunto set my hand.

JOSEPH DONAT BERGERON.
